UNITED STATES PATENT OFFICE.

WILLIAM M. SMITH, OF MERIDEN, CONNECTICUT, ASSIGNOR TO THE
MERIDEN BRITANNIA COMPANY, OF SAME PLACE.

COFFIN-HANDLE SOCKET.

SPECIFICATION forming part of Letters Patent No. 244,681, dated July 19, 1881.

Application filed June 13, 1881. (No model.)

To all whom it may concern:

Be it known that I, WM. M. SMITH, of Meriden, in the county of New Haven and State of Connecticut, have invented a new Improvement 5 in Coffin-Handle Sockets; and I do hereby declare the following, when taken in connection with the accompanying drawings and the letters of reference marked thereon, to be a full, clear, and exact description of the same, and 10 which said drawings constitute part of this specification, and represent, in—

Figure 1, a front view; Fig. 2, a section on line *xx*.
This invention relates to an improvement in 15 the construction of the sockets by which coffin-handles are attached, the object being to combine several materials in the socket, whereby a more ornamental and tasteful socket may be produced; and it consists in constructing the 20 body of the socket with arms projecting from the body of the socket recessed upon their under side to receive and hold the border-pieces, as more fully hereinafter described.

A represents the base of the socket, constructed with the usual ears, *aa*, to receive the handle-lever, and provided with screw-holes for its attachment to the coffin. Projections B are made at each corner to extend from the body of the socket outward and form a corner 25 or angle ornament, but recessed upon their under side, as seen in Fig. 2, to receive the ends of the border-pieces C. These border-pieces may be made of various kinds of wood or material covered with fabric, or metal of a different color from that of the body of the socket. 30 These pieces are cut to the requisite length to extend from one projection to the next, pref-

erably perforated, as at *b*, so that tacks may be inserted through the projections into the border-pieces to secure the border to the projections. 40

The projections B may be made in any ornamental shape, it only being essential that they be recessed upon their under side to receive and hold the border-pieces. In case of a polygonal shape, the projections are best made at 45 each angle.

Instead of securing the border-pieces by tacks, as shown, these pieces may be introduced at the time the handle is placed upon 50 the coffin, and held in place simply by the projections overlapping the ends of the pieces, or the socket may be applied to a base, so that the projections would clamp the bordering-pieces upon the base. 55

Intermediate similar projecting pieces may be made upon the sides of the body of the socket, so as to form an ornament over the border-pieces, or the projecting pieces may be at the sides only and not at the angles, they being 60 recessed upon their under side, so as to extend over the border-pieces and be the means of securing those pieces in place.

I claim—

The herein-described coffin-handle socket, 65 consisting of the metal center, with projections extending therefrom recessed upon their under side, combined with border-pieces introduced to and held in place by said recessed projections, substantially as described.

WILLIAM M. SMITH.
